Primary Examiner — T. Chase Nelson*Assistant Examiner* — Jonathan J Han(74) *Attorney, Agent, or Firm* — Edell, Shapiro & Finn, LLC(57) **CLAIM**

The ornamental design for a shoe sole, as shown and described.

DESCRIPTION

FIG. 1 is a perspective view of a shoe sole showing my new design;

FIG. 2 is a bottom plan view thereof;

FIG. 3 is a top plan view thereof;

FIG. 4 is a right side view in elevation thereof;

FIG. 5 is a left side view in elevation thereof;

FIG. 6 is a front view in elevation thereof; and,

FIG. 7 is a rear view in elevation thereof.

The broken line illustration of environmental structure in FIGS. 3 and 6 is not part of the claimed design.

1 Claim, 7 Drawing Sheets(56)
